UNITED STATES PATENT OFFICE.

GEORGE R. KIDDER, OF IMLAY CITY, MICHIGAN.

IRONING-BOARD.

SPECIFICATION forming part of Letters Patent No. 393,245, dated November 20, 1888.

Application filed March 10, 1888. Serial No. 267,068. (No model.)

To all whom it may concern:

Be it known that I, GEORGE R. KIDDER, of Imlay City, in the county of Lapeer and State of Michigan, have invented a new and useful Improvement in Ironing-Boards, of which the following is specification.

My invention consists in an improved ironing-board, hereinafter fully shown and described.

10 Figure 1 is a longitudinal section on the line *xx*, Fig. 2; and Fig. 2 is a bottom plan view.

A represents one end of an ordinary table, and B represents a narrow pointed board, commonly called an "ironing-board."

15 C represents a cleat fastened to the under side of the ironing-board B, near the broad end thereof, which is substantially as thick as the table-top A.

F represents a clamp pivoted to cleat C in any convenient manner.

A cheap and easy way of pivoting the clamp F to the cleat C is to bore a hole through the clamp, enlarging this hole somewhat toward the lower surface of the clamp, as shown in Fig. 1, and then fastening the clamp to the cleat by a screw-bolt, D, and washer E. I prefer to make the end of the clamp F to project somewhat beyond the end of the board B, as shown in the drawings, to facilitate attaching the board to the table A. The other end of the clamp F is bifurcated, having two arms, O O, carrying between their ends the roller L, mounted on pin M.

I represents a cleat secured to the under side of the board B, near its tapering end, and H represents a leg attached to cleat I by an ordinary hinge, J.

G represents a piece of wood secured to leg H by an ordinary hinge, K, and having its other end made in the form of a curved wedge, as clearly shown in Fig. 1, lying above the

roller L and adapted to play in the slot between the arms O O.

The operation of my invention is as follows: The leg H being folded up, the end of the ironing-board is presented to the edge of the table A in such manner as to embrace the table-top between the clamp F and the under side of the board B. This operation is facilitated by bringing the projecting end of the clamp 50 against the under side of the table-top, thus forming a guide. The leg H is then let down to support the other end of the board B, and this causes the curved wedged end of the piece G to depress the roller L, thereby forcing the clamp F tightly against the under side of the table-top and holding the ironing-board B firmly to the table. It will thus be seen that the ironing-board is supported at one end by the table and near the other end by leg H, so 60 that it is firm. To remove the ironing-board from the table, all that is necessary is to fold up the leg H, when the clamp F lets go of the table-top and the board may be readily removed.

What I claim as my invention, and desire to secure by Letters Patent, is—

1. An ironing-board having at one end a pivoted clamp, one end of which is bifurcated and provided with a roller, and at the other 70 end a hinged supporting-leg, a wedge adapted to operate said clamp, hinged to and operated by the leg, substantially as described.

2. In an ironing-board, the combination of the clamp F, hinged leg H, and wedge G, 75 hinged to leg H, substantially as shown and described.

GEORGE R. KIDDER.
